Primary Examiner — T Chase Nelson*Assistant Examiner* — Kelly L Gross(57) **CLAIM**

The ornamental design for an incubator for hatching eggs, as shown and described.

DESCRIPTION

FIG. 1 is a front perspective view of an incubator for hatching eggs, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof, showing the components of the design separated for clarity of illustration; and,

FIG. 10 is an enlarged detail view of area 10 in FIG. 9. The broken lines in the drawings illustrate the portions of the incubator for hatching eggs, which form no part of the claimed design.

The dash-dot-dash broken lines encircling the enlarged views are for annotative purposes only and form no part of the claim thereof.
